UNITED STATES PATENT OFFICE.

FRANK J. HUSBANDS, OF LOS ANGELES, CALIFORNIA, ASSIGNOR, BY MESNE ASSIGNMENTS, TO ACME TRAFFIC SIGNAL COMPANY, A CORPORATION OF CALIFORNIA.

TRAFFIC REGULATOR.

Application filed March 15, 1921. Serial No. 452,580.

To all whom it may concern:

Be it known that I, FRANK J. HUSBANDS, a citizen of the United States, residing at Los Angeles, in the county of Los Angeles 5 and State of California, have invented new and useful Improvements in Traffic Regulators, of which the following is a specification.

This invention is a traffic regulator providing signalling means at points of traffic intersection, the signals for the respective points of traffic intersection being either independently locally controlled or simultaneously controlled from a central station.

15 The local controlling means is arranged so that the operator may control the signals so as to signal for traffic movement in one of the cross directions and at the same time signal for stopping of traffic movement in 20 the other cross direction, and may then change the signals so as to signal for stopping of traffic movement in the first direction and for movement of traffic in the cross direction. The local controlling means is 25 also so arranged that when an operator stops controlling the mechanism locally, it will again be controlled by the central station.

The central station controlling means is automatic in its action, and is arranged to 30 first position the signals at a point of traffic intersection so as to signal for stopping of traffic in the cross directions for a short interval, say five seconds, and to then change the signals controlling traffic in one direction so as to signal for movement of traffic, while maintaining the signals for the cross direction of traffic in a position to signal for stopping of traffic. After a predetermined interval, say thirty seconds, the signals arranged for signalling for traffic movement 35 are again returned to a position signalling for stopping of traffic movement, so that traffic is again stopped in the cross directions. This condition exists for another 40 short interval, and the signals controlling traffic in the second of the cross directions are then moved so as to signal for traffic movement, while the signals controlling traffic in the first of the cross directions remain 45 unchanged, so as to signal for stopping of said traffic. This condition is maintained for a period of time equal to that previously described, and the signals are then again moved so as to signal for stopping of traffic 50 in cross directions for another short interval.

This cycle of operation is repeated indefinitely, and when it is desired to stop using the system, the manual manipulation of switches at the central station will cause all of the signalling elements to move into 60 non-signalling position.

The invention will be readily understood from the following description of the accompanying drawings, in which

Figure 1 is a vertical section through one 65 of the signalling elements with the front of its casing broken away.

Fig. 2 is a transverse section on the line 2-2 of Fig. 1.

Fig. 3 is a detail section on the line 3-3 70 of Fig. 1.

Fig. 4 is a vertical section on the line 4-4 of Fig. 2.

Fig. 5 is a diagrammatic showing of several points of traffic intersection, such as are 75 formed by intersecting streets, units of the improved traffic regulator being positioned at the several points of traffic intersection.

Fig. 6 is a diagrammatic showing of the traffic regulating system including the central control station, one of the signalling units, and the local control for the same, the mechanism being actuated by the central control station, with the signals in the position which is maintained for a short interval, and signalling for stopping of traffic in 80 the cross directions.

Fig. 7 is a similar view, but not showing the local control station in detail, and showing the next position of the signals 90 of a unit, in which the signals are arranged for traffic stopping in one direction and for traffic movement in the cross direction.

Fig. 8 is a similar view showing the next position of the signals where traffic in cross directions is again stopped for a short interval.

Fig. 9 is a similar view showing the next position of the signals, signalling for traffic movement in the first direction and for stopping of traffic in the cross direction.

Fig. 10 is a diagrammatic showing of one of the signalling units and the local control for the same, the latter being operated so as to signal for traffic movement in one direction and for traffic stopping in the cross direction.

Fig. 11 is a similar view showing the next succeeding step where the local control mechanism is moved back to a neutral position.

sition, maintaining the signals as previously described, and causing the illuminating means employed in connection with the signals to be energized in accordance with the signals.

Fig. 12 is a similar view showing a second neutral position to which the local controlling mechanism is then moved, the signals remaining unchanged.

10 Fig. 13 is a similar view showing the second operating position of the local control to which the latter is next moved, and in which the signals are arranged for stopping of traffic in the first direction and for traffic movement in the cross direction.

Fig. 14 is a perspective diagram of one unit of the system showing the wiring for the respective signalling elements.

15 Fig. 15 is a perspective view of the switch 20 for the local control of a unit.

The improved traffic regulator is illustrated as employed in connection with points of traffic intersection as shown in Fig. 5, in which parallel streets or roads are shown at 25 A and parallel cross streets or roads are shown at B. One of the signalling units of a traffic regulator is positioned at each intersection of streets A and B, and each unit consists of signalling elements mounted at 30 the respective corners of the traffic intersection. Each signalling element has two semaphore arms, one of which signals for traffic movement, while the other signals for stopping of traffic. As an instance of this 35 arrangement the semaphore arms may have the words "Go" and "Stop" thereon. Each signalling element is so arranged that either the go or the stop semaphore may be projected into signalling position, while the other semaphore is retracted within the signalling element so as not to show.

40 In the drawings two streets are shown intersecting in each instance, thereby forming four corners at a traffic intersection and necessitating the employment of four of the 45 signalling elements for each unit. It will be obvious that when more than two streets intersect, a greater number of corners are formed so as to necessitate the employment 50 of a greater number of signalling elements for each unit. In every case a signalling element is provided upon each corner irrespective of the number of corners at the intersection, and each of the signalling elements is arranged to control traffic along the 55 street at the side of the corner along which traffic naturally moves in a direction toward the signalling element.

60 The signalling elements of a unit are so arranged that the two elements of a unit which control traffic in opposite directions along one line of traffic intersection, may be dependently operated so as to signal for either traffic movement or stopping of traffic 65 in said opposite directions. The signalling

elements controlling traffic in opposite directions along cross lines of traffic intersection, are similarly dependently controlled. The signalling elements for one direction of traffic may signal for either traffic movement 70 or stopping of traffic, while the signalling elements for a cross direction of traffic show the opposite signal, the controlling of the signalling element being either from a central station or from a local control, and being so arranged that the signals may be reversed, so as to signal for traffic movement and stopping of traffic in cross directions, and in changed relation to the first signalling position. The mechanism is also so arranged that all of the elements of a unit 75 may signal for traffic stopping between the changes in direction of traffic movement, and means are also provided for retracting both semaphores of each of the signalling 80 elements comprising a unit, so that the entire system becomes inoperative.

85 The respective signalling elements include a casing 1 mounted upon a support 2. The casing is, preferably, partitioned by walls 3 spaced inwardly from the side walls of the casing so as to form outer longitudinally extending spaces 4, and a central longitudinally extending chamber 5. A support 6 extends upwardly within chamber 5 and carries a transversely extending cylindrical shell 7 adjacent the upper end of casing 1. A rod 8, preferably, projects from this shell 9 above casing 1 and supports a closure cap 9 for the casing. The shell 7 is transversely 100 divided by a partition 10. Diametrically opposite field windings 11 are supported by shell 7 within the portions thereof at the respective sides of partition 10, and diametrically extending armatures 12 are journaled in each portion of the shell between the field windings, so that the armatures 105 may be swung from position in diametrical alignment with the field windings to a position at right angles thereto. These armatures are journaled upon a bearing 13 provided in partition 10, and at their opposite ends are journaled in the end walls of shell 7, so that outwardly extending shafts 14 of these armatures project into spaces 4. Counterweights 15 extend laterally from shafts 14 in diametrical alignment with armatures 12, and semaphore arms 16 extend laterally from shafts 14 in diametrical alignment with counterweights 15 and armatures 12, and extend from shafts 14 in directions 110 opposite to that of the counterweights.

115 The respective armatures, counterweights, and semaphores within shell 7, are arranged at right angles to one another, so that when one of the semaphores projects laterally from casing 1, the other semaphore will be 120 retracted within the space 4 provided by the casing. It will be noted that the semaphore which is projected from the casing 130

will have its armature in alignment with the field windings 11, and that the semaphore which is retracted will have its armature turned at right angles to the field windings.

One of the semaphores is a "go" signal and the other semaphore is a "stop" signal, and for this purpose the respective semaphores may have the words Go and Stop indicated thereon as shown at 18. Illuminating means are employed in connection with the stop and go signals, and for this purpose a casing 19 is mounted upon support 6 and projects laterally from casing 1 below the semaphores. This casing is divided by partition 20 into lamp boxes 21 having illuminating means, such as usual incandescent lamps 22. Transparent bull's eyes 23 are provided in the respective lamp boxes and are distinctively colored, red and green, for example, so that illumination of the same will signal for traffic stopping and traffic movement respectively.

In operation the field winding of a signalling element is energized and the armatures for the respective semaphores are also energized. The polarity of the current through the armatures may be changed with relation to the polarity of the current through the field windings, so that the armatures may be reversely rotated in either direction. It will be understood that this reverse rotation of the armatures will swing the semaphores up and down into either signalling or nonsignalling position. Since the two armatures and the two semaphores of a signalling element are arranged at angles of approximately 90° to one another, it will be seen that when the armatures are thus rotated, one semaphore will be up while the other is down, and that by reversing the direction of rotation of the armatures, the first semaphore will be swung down and the second semaphore will be swung up. As shown in Figure 1, the shell 7 is provided with resilient stops 7^a arranged to be engaged by the counter-weights 15 for defining the two extreme positions of the semaphores 16. It is by means of these stops that the rotational movement of the armatures is limited so that the extreme positions of the semaphores will be predetermined at all times.

If the electrical current employed in the operation of the signalling system is direct current, the field windings will be energized with a current of uniform polarity and the armatures will be energized by a current, the polarity of which may be reversed so as to cause rotation of the armatures relative to the field windings. If alternating current is employed, so that the polarity of the current through the field windings and the armatures is constantly reversing, the armatures are so arranged that the alternating

current through the same may be reversed with relation to the alternating current through the field windings, in order to provide the necessary relatively opposite polarity between the field windings and the armatures for causing rotation of the latter.

The illuminating means for a signalling element is so arranged, that when the Go semaphore is shown the green bull's eye will be lighted, and when the Stop semaphore is shown the red bull's eye will be illuminated. A suitable audible signal shown as a bell 25 is also provided in casing 1 and is arranged to be sounded whenever the semaphore displayed by the signalling element is changed.

A suitable manually controlled switch mechanism is provided for the signalling elements comprising each unit, in a position convenient to an operator, and this local control mechanism makes and breaks necessary electrical circuits leading from the same through the field windings, the armatures, the lamps, and the bells of the signalling elements comprising a unit. The central control station which controls the operation of a plurality of signalling units, has a suitable automatically actuated make and break mechanism for circuits leading from a suitable source of electrical energy through the same and thence to the respective local control mechanisms. The system is so arranged that a local control mechanism may be thrown out of operation, so that the unit with which it is associated will be controlled by the central station, or the local control may be brought into use for actuating the unit, and in this latter case the central control station will continue to function without relation to the particular unit which is being locally controlled.

In Fig. 6 I have diagrammatically shown one of the signalling units with its local control and also the central controlling station with the connections between the same and the local control. The signalling unit is being operated by the central station.

The armatures 12 of the two signalling elements which control traffic in opposite directions along one way of traffic intersection are shown at C, arranged for dependent actuation, and the armatures of the two signalling elements for traffic along a cross way, are shown at D. The field windings 11 for armatures C and D are arranged in parallel as shown at E.

The local control comprises a casing 30 carrying a plurality of circumferentially arranged electric contacts, and a disc 31 carrying co-operating contacts is journaled to the casing for rotation by means of lever 32 with relation to the same so as to make or break connections between the two sets of

contacts. The casing carries sets of contacts F, G, H, I and J, each consisting of five contacts 33, 34, 35, 36 and 37. The casing also supports a contact group K, having contacts 38, 39 and 40, and sets of contacts L and M each consisting of contacts 41 and 42.

The disc 31 carries contact makers 43, 44, 45, 46 and 47 co-operating with the sets of contacts F to J respectively. These contact makers are of a length sufficient to bridge any two adjacent contacts of their respective co-operating sets, as clearly shown in Fig. 6. The disc also carries contact makers 48 and 49 co-operating with the set of contacts K, and so arranged as to disengage contacts K, or have contact maker 49 bridge either contacts 38-39 or 39-40, or have contact maker 48 bridge contacts 38-39. Contact makers 50 and 51 carried by disc 31 co-operate with contacts L and M so as to either bridge contacts 41-42, or disengage the latter.

The parts are so arranged that when contact makers 43 to 47 bridge contacts 33-34, as shown in Fig. 6, the set of contacts K are disengaged, by contacts 48-49, and sets of contacts L and M are bridged by contact makers 50-51. When the parts are moved to the position shown in Fig. 10, contact makers 43-47 bridge contacts 34-35, the set of contacts K are still disengaged by contact makers 48-49, and contact makers 50-51 are moved beyond bridging position with relation to sets of contacts L and M.

Disc 31 is then moved to the position shown in Fig. 11, where contact makers 43-47 bridge contacts 35-36, contact maker 49 bridges contacts 38-39, and contact makers 50-51 have passed beyond sets of contacts L and M. In the next position, shown in Fig. 12, disc 31 has been further rotated just sufficient to cause contact maker 49 to bridge contacts 39-40 instead of 38-39, while contact makers 43-47 still bridge contacts 35-36, and contact makers 50-51 are beyond contacts L and M.

In the next and last position of disc 31, during one direction of rotation of disc 31, the parts are shown in Fig. 13, with contact makers 43-47 bridging contacts 36-37, contact maker 49 beyond the set of contacts K with contact maker 48 bridging contacts 38-39, and contact makers 50-51 beyond contacts L and M. During reverse rotation of disc 31 the contact makers and contacts are moved through the above described positions in the reverse order.

Referring to Fig. 14 it will be seen that the armatures for the signalling elements are wound in the same direction, and that the two armatures included in each of the signalling elements C, are connected by a wire 55 leading from the end of the stop semaphore armature opposite its semaphore, to the end of the go semaphore armature

which is adjacent its semaphore, and that the two armatures of each element D are connected by a wire 55^a leading from the end of the stop semaphore armature adjacent its semaphore, to the end of the go semaphore armature which is opposite its semaphore.

As shown in Fig. 6, a wire 56 connects the wires 55 for the armatures of signalling elements C, while wire 56^a similarly connects the wires 55^a for the armatures of signalling elements D. These wires 56 and 56^a are in turn connected as shown at 57.

By referring to Figs. 6 and 14, it will be seen that the opposite ends of the armature elements actuating the stop semaphores for the signalling elements C, and for the signalling elements D, are connected respectively as by wires 53 and 53^a to wires 58 and 58^a. In similar manner wires 54 extend from the opposite ends of the signalling elements C, and wires 54^a extend from the opposite ends of the armature elements controlling the go semaphores for the signalling elements D. A wire 59 connects the wires 54 and a wire 59^a joins wires 54^a.

Wires 58 and 59 are connected as shown at 60, with a manually operated switch 61 in the wire 59, and in similar manner wires 58^a and 59^a are connected as shown at 62, with a manually operated switch 63 in the wire 59^a. The switches 61-63 are arranged for depending actuation and for this purpose may be combined in a two blade single throw sw. ch.

By the arrangement as thus described, it will be seen that current of one polarity flowing through wires 58-59 or 58^a-59^a and through the armatures connected thereto and thence to the connection 57, will cause the semaphores of each element to be oppositely moved to bring the stop semaphore up and the go semaphore down, or vice versa, and furthermore the elements C and D will be oppositely actuated, i. e. if such a current in C elements moves the stop semaphores up and the go semaphores down, in the D elements it will move the go semaphores up and the stop semaphores down. It will be further observed that a change in the polarity of the current, will cause each of the semaphores to be reversely actuated, and thereby still cause the C and D elements to display opposite semaphores in a reverse arrangement.

The bells 25 of signalling elements C are arranged in parallel between the stop semaphore armature elements of said signalling elements and are shown as connected to wires 56 and 58. The bells of signalling elements D are similarly connected to wires 56^a and 58^a so that they are arranged in parallel between the stop semaphore armature elements of signalling elements D.

The incandescent lamps 22 for the respec-

tive signalling elements are connected by wires 65, and these wires for the elements comprising a unit are connected to a wire 66. The other side of one of the lamps of the respective elements are connected by a wire 67, while the other side of the other lamps for the respective elements are connected to an extension of wire 58. The red and green lamps of one of the sets of signalling elements C or D are connected between wires 66-67 and wires 66-58 respectively, while the red and green lamps for the other set of elements C or D are oppositely arranged between wires 66-58 and wires 66-67. By this arrangement it will be seen that a closed circuit through wires 66-67 will illuminate the red and green lamps for signalling elements C and D respectively, while a closed circuit through wires 66-58 will similarly illuminate lamps of the opposite color for elements C and D.

The field windings for the elements of a unit are connected at one end to wire 67, and the opposite ends of the field windings are connected to a wire 69.

The contacts 34 of contact sets F to J are connected respectively to wire 69, wire 67, wire 58, connection 57, and connection 62; and contacts 33 of the respective sets lead to the central control station. When a unit is centrally controlled as shown in Fig. 6, switch 61-63 is open and disc 31 is turned until the contacts 33-34 of contact sets F to J are bridged, so that current flows directly from the central station to the signalling unit and the local control is inoperative. This condition of the local control is maintained throughout the operation of a unit from the central control.

The central control station is provided with a uniformly rotating shaft having contact discs N to W fixed thereon. The contact makers of these discs are positioned in a definite circumferential relation to one another for closing circuits in a predetermined order through the respective signalling units, and contacts 70-71 co-operate with the respective discs so as to be bridged by the contact makers thereof. The arrangement of the contact makers of the discs N to W will be described by reference to Fig. 6, the rotation of said discs being clockwise.

Discs N and O have diametrically opposite arcuate contact makers 72, so that during a cycle of operation, a circuit is closed through their contacts 70-71, by one or the other of these contact makers during the respective interval for traffic movement in cross directions, for lighting the lamps of the signalling units. It will be noted that the contact makers 72 of the discs N and O are of different lengths, and for the purpose of maintaining the lamps for the respective signals illuminates for periods corresponding to the

periods which the signals occupy display position, because in actual practice it is generally necessary that one semaphore or the other be displayed for a greater or less interval than the other in order to take care of a condition in which the traffic along one street is greater than the traffic along an intersecting street.

Disc P is provided with diametrically opposite contact makers 72 and 72^a so arranged that contact maker P72 will engage contacts P70-71, just after contact maker O72 disengages its contacts 70-71; and the contact maker P72^a engages its contacts just after contact maker N72 disengages contacts N70-71. Contact makers P72 and P72^a are of such length as to each bridge contacts P70-71 during one of the short intervals when all elements of a unit are at stop, and at the start of the succeeding period of time when one set of elements C or D are changed to go. Contact maker P72 controls the set of elements D and contact maker P72^a controls the set of elements C of a signalling unit. The spaces between contact makers P72 and 72^a during which the circuit through contacts P70-71 is broken, are of such length as to maintain the signalling elements in their two reversed arrangements of go and stop positions for cross directions for the required interval of time.

The contact maker 72 of disc Q is arranged to bridge contacts Q70-71 during the interval when contact maker P72 first bridges contacts P70-71 so that all of the elements of a unit will be in stop position. Contact maker Q72 passes beyond its contacts 70-71 at the end of the short interval, and at the beginning of the period of time when contact maker P72 bridges its contacts 70-71 with the rear portion of said contact maker P72, and when one set of elements, shown as elements D, is changed to go position.

The contact maker 72 of disc R bridges its contacts 70-71 during the final portion of the bridging of contacts P70-71 by contact maker P72, so that a circuit is closed through contacts R70-71 at the end of the short interval when all signals are in stop position, as controlled by contact maker Q72, and when the set of elements D is changed to go position.

The contact maker 72 of disc S and the contact maker 72 of disc T are diametrically opposite the contact makers 72 of discs Q and R, and function with relation to contact maker P72^a in manner similar to that previously described in connection with contact maker P72 and contact makers Q72 and R72. In other words, the contact maker S72 controls the short interval when all elements are at stop and which is prior to the movement of C elements to go position, and the contact maker T72 controls this move-

ment of elements C to go position. It will be understood that the spaces upon discs Q and S between contacts Q72 and S72 break their corresponding contacts during the respective reverse arrangements of signalling elements C and D for go and stop in cross directions, and also during the succeeding short intervals when all the elements are at stop. In similar manner the spaces between contact makers R72 and T72 break their corresponding contacts during the short intervals when all elements are at stop and during the succeeding intervals when elements C and D are in their reverse arrangements for signalling in cross directions.

The contact makers 72 upon discs U and V are arranged to reverse the polarity of the current through the armatures of the signalling elements, and these contact makers are diametrically opposite one another, and bridge contacts U70—71, and V70—71 respectively, so as to function in conjunction with contact makers O72, P72, Q72, R72 and in conjunction with contact makers N72, P72^a, S72^a, T72^a respectively.

Thus it will be noted that contact maker U72 bridges its contacts, while contact maker P72 first bridges its contacts, and continues to bridge its contacts as contact makers P72 and Q72 bridge their contacts to move all elements to stop position for a short interval. As contact maker Q72 passes beyond bridging position, and contact maker R72 is moved into bridging position to cause the C and D elements to display stop and go signals respectively, contact maker U72 continues to bridge its contacts, and as contact maker R72 passes beyond bridging position contact maker U72 similarly moves beyond bridging position.

At the end of the portion of the cycle of operation during which the C and D elements remain in stop and go position respectively, and when contact makers P72^a and S72 bridge their contacts, to return all elements to stop position for another short interval, contact maker V72 bridges its contacts, to reverse the polarity of the current through the armatures, and when contact makers P72^a and S72 pass beyond bridging position, and contact maker T72 bridges its contacts to move the elements C and D to the reverse opposite signalling position, contact maker V72 remains in bridging position, and passes beyond such bridging position as contact maker T72 similarly passes beyond bridging position.

The signalling elements C and D will then remain in their reversed opposite signalling position during the remainder of a cycle of operation, and until contact makers P72, Q72 and U72 again bridge their contacts to again move all elements to stop position for the start of the succeeding cycle of operation.

Disc W is provided with diametrically opposite contact makers 72 and 72^a which are similar to contact makers P72 and P72^a and which are similarly arranged. Contact makers W72 and W72^a bridge their contacts W70—71 so as to co-operate with contact makers P72 and P72^a and their contacts P70—71, for closing the circuit through the field windings E, whenever either set of signalling elements C and D are actuated, and the bridging of contacts W70—71 by contact makers W72 and W72^a also functions in conjunction with the bridging of contacts Q70—71 and S70—71 by their contact makers, to close circuits through the armatures of C and D signalling elements respectively.

In operating the traffic regulator from the central station, disc 31 of the local control for each signalling unit, is left in the position shown in Fig. 6 and the switch 61—63 for each unit is opened.

With the parts as shown in Fig. 6, the signalling elements of a unit are all displaying stop semaphores for one of the five second intervals between traffic movement in cross directions. Just previous to this positioning of the semaphores, the C elements were displaying go semaphores, and the D elements were displaying stop semaphores, so that the controlling means are shown in their arrangement which has just actuated the C element to bring the same to stop position.

As will be readily seen, contact maker P72 bridges its contacts so as to close a circuit from one of the lead wires 75 through contacts P70—71 and thence to a wire connected at its other end to contact G33, which in turn is connected to contact G34 by contact maker 44. Contact G34 is connected to wire 67 leading to field windings E. The circuit through the field windings is completed by wire 69, contact F34, contact maker 43, contact F33, contact W71, contact maker W72, contact W70 and the second lead wire 76.

The armatures of the C elements have been energized by a circuit from lead 75, through contact Q70, contact maker Q72, contact Q71, and a split wire 81 leading to contact L42 and to contact H32. From contact L42 the circuit continues through contact maker 50, contact L41, a wire leading to wire 59 and thence to wires 54 and through the go semaphore armatures of elements C.

In similar manner the circuit continues beyond the split, through contact H33, contact maker 45, contact H34, a wire leading to connection 60, and thence by wire 58 and wires 53 to the stop semaphore armatures of elements C. The circuits through the go and stop semaphores of elements C are completed through wires 55, wire 56, connection 57, a wire leading to contact L34, contact

maker 46, contact I33, a wire leading to contact V70 and having an extension leading to contact U71, contact maker U72, contact U70 and thence to lead 76. The polarity of the current in this circuit is such as to swing the armatures of the signal elements upon their pivots and change said elements from their previous go position to stop position. It will be noted that the circuits through 10 the armatures of the D elements are broken, so that said armatures are not energized and the D elements will therefore remain in their previous position displaying stop semaphores, it being understood that the 15 mounting of all of the elements is such that they will remain in any one of the two extreme positions to which they are moved.

At the end of the five second interval the discs forming the controlling mechanism 20 will have rotated to the position shown in Fig. 7 where contact maker Q72 has moved beyond its contacts Q70—71 and contacts R70—71 are bridged by contact maker R72.

With the parts in this position, a circuit 25 is closed through the field windings E in manner similar to that previously described and the closed circuit is formed which may be traced from lead 75 through contact R71, contact maker R72, contact R70, and thence 30 to a split wire 80, one split of which leads through contacts M (Fig. 6) bridged by contact maker 51 and to wire 59^a, from thence through wires 54^a to the go semaphore armatures of elements D. The other 35 split of this wire leads through contact J33 (Fig. 6), contact maker 47, contact J34, to the connection 62 and thence through wire 58^a and wires 53^a to the stop semaphore armatures of elements D. A common return 40 is provided from wires 55^a through wire 56^a to the connection 57, and thence back to lead 76 by way of contact maker U72, as 45 previously described.

It will thus be seen that the armatures of 50 elements D are energized so as to swing the semaphores of these elements to their opposite position, or in other words to a position displaying the go semaphores. The circuit through the armatures of the C elements 55 having been broken by contact maker Q72 passing beyond its contacts, these elements will continue to display the stop semaphores.

The parts remain in this position during 60 one of the intervals for movement of traffic, and during which the control discs rotate to break contacts P70—71, R70—71, U70—71 and W70—71, so that current will not be unnecessary expended while the signals remain in said position. At the end of the interval for traffic movement, the control discs will have rotated to the position shown in Fig. 8, and contact makers P72^a and W72^a then bridge their contacts to close a circuit through the field windings E as previously

described. At the same time a circuit is 65 closed from lead 75, through contact V71, contact maker V72, contact V70, the wire leading through the local control to connection 57, wire 56^a and wires 55^a to the armatures of the D elements. The return from the armatures is by way of wires 53^a and 54^a to wires 58^a and 59^a, which are connected, as previously described, to the split wire 80. The circuit continues through this split wire 70 and thence through an extension of the same beyond contact R70 to contact S70, thence through contact maker S72^a and contact S71 to lead 76. It will thus be seen that the armatures of the go elements are energized 75 by a current of opposite polarity to that previously employed, and as a consequence the armatures will be rotated to bring down the go semaphores and display the stop semaphores. The unit is thus again in the position for one of the short intervals during 80 which the traffic stops in both directions.

As the rotation of the control discs continues they will assume the position shown in Fig. 9 and wherein the C elements are 85 actuated to display go semaphores. In this position contact maker S72 has moved beyond its contacts, and contact maker T72 bridges its contacts. Contact makers P72 and W72 still bridge their contacts so as 90 to form a circuit through the field windings E, and contact maker V72 continues to bridge its contacts so that a circuit is formed which may be traced from lead 75 through the contact maker V72 to connection 57, as just described. The circuit continues 95 through wire 56 to wires 55 and from thence through the armatures of the C elements. The return from the armatures is by way of wires 53 and 54 to wires 58 and 59. The circuit continues from wires 58 and 59 through split wire 81, as previously 100 described, and an extension of this split wire leads beyond contact Q71 to contact T70. From thence the circuit continues through 105 T72 and contact T71 to lead 76. The circuit, as thus described, energizes the armatures of the C elements by a current of reversed polarity to that first described, so that the go semaphores of the C elements will be 110 displayed while the stop semaphores are 115 swung down. The circuit through the armatures of the D elements being broken, these elements will continue to display stop semaphores.

During the respective intervals when the 120 elements of a unit signal for traffic movement in the respective cross directions, the elements displaying stop semaphores will have their red bull's eyes illuminated, and the elements displaying go semaphores will 125 have their green bull's eyes illuminated.

For this purpose, one of the banks of lamps, as previously described, and includ-

ing red and green bull's eyes for the D and C elements respectively is shown at X, while the other bank of lamps including green and red bull's eyes for the D and C elements respectively is shown at Y.

Wire 66-67 are connected to the bank of lamp X, while wires 66-58 are similarly connected to the bank Y.

- 14 As contact makers P72, R72, U72, and W72 move beyond their contacts, and the C elements displaying stop semaphores, and the D elements displaying go semaphores, as shown in Fig. 7, contact maker O72 will have already passed beyond its contacts, and
- 15 contact maker N72 will bridge its contacts and remain in bridging position until just before the start of the interval when the signal elements display go semaphores, and the D elements display stop semaphores.
- 20 When in this position a lamp circuit is closed which may be traced from lead 75 through an extension from contact P70 to contact N70, through contact maker N72, contact N71, an extension from contact Q71, and
- 25 thence through the split of wire 81 connected to wire 58. The circuit continues through the bank of lamps Y and thence through wire 66 to lead 76.

When the signal elements display go semaphores, and the D elements display stop semaphores, as shown in Fig. 9, and contact makers P72^a, T72, V72, W72^a have moved beyond their contacts, contact maker N72 will have already moved beyond its contacts and contact maker O72 will bridge its contacts, and remain in said position until just before the interval again starts during which the semaphores are as shown in Fig. 7. With contact maker O72 bridging its contacts, a lamp circuit is closed through the X bank of lamps, which may be traced from lead 75, through the extension to contact N70 and which also leads to contact O70, through contact maker O72, contact O71, an extension from contact P71, and thence, as previously described, to wire 67. The circuit continues through the bank of lamps X and thence through wire 66 to lead 76.

With the elements of a unit in the position shown in Fig. 9, a cycle of operation is completed, and the signals remain in this position while the control discs rotate so as to bring the same back to the position shown in Fig. 6. It will be noted that with the parts in the position shown in Fig. 6, armatures C are energized by a current of reversed polarity from that utilized when the parts were as shown in Fig. 9, and as a consequence when the C armatures are thus energized, they will rotate to bring down the go semaphores and display the stop semaphores. The D armatures not being energized, they will continue to display stop semaphores, and the parts are thus again ar-

ranged for the short interval when traffic is halted, and which arrangement is shown in Fig. 6.

In order that the entire regulating system may be caused to become inoperative, by concealing both sets of semaphores for the units, a switch 83-84 is provided at the central station, which when opened will disconnect the go semaphore armatures of both sets of elements, and consequently as the cycle of operation continues, the stop semaphores of the elements will be drawn down without a corresponding upward swing of the go semaphores. When all of the semaphores have been thus moved down, the central control discs may be stopped and thereby leave the system in inoperative position.

The switch 83-84 has one blade 83 arranged in the split of wire 81 leading to contact L42, and its other blade 84 positioned in the split of wire 80 which leads to contacts M, so that opening said switch will disconnect the go semaphore armatures, as will be readily understood, and for the purpose just described.

The operation of the local control for a unit of the system will be understood by reference to Figs. 10-13. Switch 61-63 is closed, and through handle 32, the disc 31 is turned from the position shown in Fig. 6 to the position shown in Fig. 10. In this position contact makers 43-47 bridge their contacts 34-35; and contact makers 50 and 51 disconnect their contacts L and M. The armatures of the C and D elements will then be energized, and since these armatures are oppositely connected, one set of elements, shown as the C elements, will display go semaphores, while the D elements display stop semaphores.

Circuits are closed as follows: The field winding circuit is from lead 76 through wire 79, connected to contact G35 by a wire of the local control mechanism, through contact maker 44, contact G84, wire 67, the field windings E, wire 69, contact F34, contact maker 43, and contact F35, which is connected to a wire of the local control leading to a wire 85 connected to lead 75.

The circuit through the armatures is from lead 76 through wire 79 connected by a wire of the local control mechanism to contact I35, through contact maker 46, contact I34, leading to connection 57, and thence through the armatures of the respective sets of elements, as previously described. Beyond the armatures the circuits continue through wires 58 and 59 and through wires 58^a and 59^a connected respectively by the closed switch 61-63. Beyond connection 60 of wires 58-59, the circuit continues to contact H34, through contact maker 45, and contact H35 which is connected to the wire leading to wire 85 and thence to lead 75. Beyond con-

nection 62 of wires 58^a—59^a, the other part of the circuit continues to contact J34, through contact maker 47, contact J35 and to the wire leading to wire 85 connected to lead 75.

As soon as the armatures have been thus moved to display the signals as described, disc 31 is advanced to a neutral position shown in Fig. 11, when contact makers 10 43—47 bridge their contacts 35—36, with contact makers 50 and 51 still beyond their contacts; and wherein contact maker 49 bridges contacts 38—39. The circuits through the armatures are then broken in 15 order to conserve electrical energy, but a lamp circuit is closed through the bank of lamps Y in order that the C and D elements which display go and stop semaphores respectively, will also show green and red lights respectively. This lamp circuit is from lead 76, through the wiring of the local control as previously described, to wire 66, thence through the Y bank of lamps to wire 58, thence through a wire leading beyond connection 60 to contact 38, through contact maker 49, contact 39, through a wire leading from the same to contact J36, through contact maker 47, and contact J35 to the wire connected to wire 85 leading to 20 lead 75.

The parts are allowed to remain in this position as long as it is desired to permit traffic movement and stopping of traffic in the cross directions, and then disc 31 is advanced until contact makers 43—47 bridge their contacts 36—37, with contact makers 50 and 51 beyond their contacts, and contact maker 38 bridging contacts 38—39 as shown in Fig. 13. The armatures of the respective 25 sets of elements are then energized by current of reversed polarity, so as to change the semaphores displayed by the respective elements, in order that the C elements will show stop signals while the D elements display go semaphores.

The field winding circuit is now formed from lead 76, through wire 79, a wire connected to contact G35 which is in turn connected to contact G36, through contact maker 44, and contact G37 which is connected to wire 67. The circuit continues through the field windings, wire 69, a wire leading from the same to contact F37, contact maker 43, contact F36 connected to contact F35, and thence to the wire leading to wire 85 and to lead 75.

The armature circuits are from lead 75 through wire 85 to contact H35 connected to contact H36, and thence through contact 30 maker 45, and contact H37, to connection 57. The circuits continue through the armatures of the respective sets of elements, as previously described, and then through wires 58 and 59, and through wires 58^a and 59^a connected respectively by its closed switch

61—63. Beyond connection 60 of wires 58—59, one part of the circuit continues by the wire leading to contact 38, through contact maker 48, contact 39, contact J36, contact maker 47, and contact J37, connected to wire 79 leading to lead 76. The other part of the circuit continues from wires 58^a—59^a through a wire leading to contact I37, through contact maker 46, contact I36 connected to contact I35, and thence through the connection to wire 79 and the lead 76.

It will thus be seen that the armatures are energized by a current of reverse polarity, and as a consequence the semaphores will move to the position shown in Fig. 13, signalling for movement of traffic in the opposite one of cross directions.

As soon as the elements are in this position, disc 31 is slightly reversely rotated to a second neutral position shown in Fig. 12, and wherein contact maker 43—47 bridge their contacts 35—36, with contact makers 50 and 51 beyond their contacts, and with contact maker 49 bridging contacts 39—40. The circuits through the armatures are now broken so as to conserve electricity, but a lamp circuit is closed through the bank of lamps X in order to light the proper lamps for the respective signals.

This lamp circuit is from lead 76 to wire 66 as previously described, through the X bank of lamps, to wire 67, and thence to contact G34 which is connected to contact 40, and through contact maker 49, and contact 39 to contact J36, and thence through contact maker 47 and contact J35 to wire 85 and lead 75.

The parts are allowed to remain in this position as long as it is desired to permit traffic movement in stopping of traffic in the reversed cross directions, and then disc 31 is moved back through its first neutral position to the position shown in Fig. 10 in order that the armatures may be again energized by a current of reversed polarity, as previously described, and in order to again change the signals so as to permit of traffic movement in the reversed cross direction. This cycle of operation for local control may be continued as long as desired, and the signalling unit may then be returned to central station control by opening switch 61—63 and rotating disc 31 to the position shown in Fig. 6 and as previously described.

Various changes may be made without departing from the spirit of the invention as claimed.

What is claimed is:

1. A street traffic regulator comprising a support, two counter-balanced signal arms, mounted on said support, means for independently moving said arms to signaling and non-signaling positions, including an armature for each arm, a field common to both armatures, and means for energizing

said field with current of one polarity and for selectively energizing said armatures independently with currents of different polarities.

5. 2. In a traffic regulator, the combination of a signal support, two armatures carried thereby with their common fields, counterbalanced signaling arms mounted on the support, the signaling arms being mounted 10 to be moved independent of each other to signaling and non-signaling positions, means for connecting the signaling arms to said armatures, and means for energizing said fields with current of one polarity and for 15 selectively energizing said armatures independently with current of different polarities.

3. In a traffic regulator, a signal support, counterbalanced signaling arms mounted on 20 the support and adapted to be independently translated to signaling and non-signaling positions, an armature for each arm, a field common to both armatures, and means for separately transmitting current to the 25 armatures to effect independent motion of the signaling arms to translate the same from one signaling position, said means being adapted to effect reversion motion of

the signaling arms by reversal of current to the armatures.

4. In a traffic regulator, a signal support, counterbalanced signaling arms movable in a vertical plane to and from signaling positions, two armatures and their fields separately connected to the signaling arms, and means for energizing said fields with a current of one polarity and for selectively energizing said armature independently with currents of different polarities.

5. In a traffic regulator, the combination 40 with a signal support of two counterbalanced signaling arms mounted by the support and movable in vertical planes to signaling and non-signaling positions independently of each other, two armatures and their common fields separately connected with such signaling arms for translating the same from one signaling position to another, and means for energizing said field with current of one polarity and for selectively energizing said 45 armatures independently with currents of different polarities.

In testimony whereof I have signed my name to this specification.

FRANK J. HUSBANDS.
